UNITED STATES PATENT OFFICE.

MAX WEISBERG, OF BUFFALO, NEW YORK.

SELF-PLAYING MUSICAL INSTRUMENT.

1,830,928.

Specification of Letters Patent. Patented Feb. 17, 1920.

Application filed September 15, 1915. Serial No. 50,760.

To all whom it may concern:

Be it known that I, MAX WEISBERG, a citizen of the United States, residing at Buffalo, in the county of Erie and State of New York, have invented certain new and useful Improvements in Self-Playing Musical Instruments, of which the following is a specification.

My invention relates to self-playing musical instruments and more particularly to that class of musical instruments wherein a plurality of tracker bars is employed, each tracker bar having a music sheet coöperating therewith.

One of the objects of my invention is the production of an instrument of this class which is automatically, as well as manually, controlled and which can be controlled from a distant point; also wherein any one of a number of selections may be played, any music sheet rewound either back to its starting point or back to a certain passage of the selection, and any selection played independent of the positions of the other music sheets, the starting of one selection serving to interrupt the selection being played at the time.

Another object of my invention is the provision of automatic playing devices within the instrument which can be positioned directly in rear of the front panel of a piano.

Another object is the production of a musical instrument particularly designed to be used in moving picture theaters where it is desired to have the selections harmonize with the pictures projected upon the screen.

A further object is to so construct the invention that the selection may be instantly changed at any time by the manipulation of push buttons or other manually-operated means, either by an operator positioned near the musical instrument or by the cinematograph operator usually located a distance from the screen onto which the pictures are projected.

A further object is to provide means whereby, when one of the selections is played, the music sheet of such selection may be automatically rewound and another composition or selection immediately started, the selections being played successively as arranged on the supporting frame carrying the successive tracker bars and their coöperating music sheets, or in any other arrangement, as may be desired.

A further object is the provision of electric devices which control the forward movement of the music sheets, there being one solenoid or other suitable electric device for each music sheet, each solenoid or device controlling a vent which leads to a pneumatic for controlling forward clutch mechanism.

A further object of my invention is the provision of means which permits any one of the music sheets to be rewound, either the entire unwound portion or any part thereof that may be desired, as for instance when the operator wants to reverse the music sheet to repeat only a certain part of the selection. Whenever a music sheet is thus reversed by manual control, the electric circuit which contains the solenoid is broken so that the next succeeding music sheet is not caused to start.

A further object of my invention is the provision of means for closing the tubes connected with the apertures or ducts in a tracker bar associated with a sheet of music that is being reversed or rewound. In the preferred embodiment of my invention I have illustrated this means in the form of a chambered chest having connection with the exhaust bellows of the instrument and having passages therein which serve as continuations of the tubes and with said tubes connect the tracker bar with the action mechanism. Each of said passages is divided into two parts and these parts are shut off, one from the other, by a pneumatic or pouch adapted to be drawn away from the two parts of the passage, and to cause one part to be placed in communication with the other.

A still further object is to provide improved mechanism of this character which is simple, durable, cheap in construction and highly efficient in operation.

My invention consists in the novel features of construction and in the arrangement and combination of mechanisms and elements to be hereinafter described and particularly pointed out in the subjoined claims.

In general terms my invention comprises a frame or frames; tracker bars supported on said frame or frames with their coöperating music sheet rollers, all of the tracker bars and music sheet rollers being mounted on a single frame, or arranged on a number of frames. Any number of these frames may be employed, depending on the number

of music sheets desired, a single music sheet or any number of music sheets being arranged on a single frame. Each of the tracker bars is provided with apertures or ducts in the usual manner, which register with apertures in the music sheet, and each of the apertures or ducts of the tracker bar is connected by means of tubing to pneumatics for causing the hammers to strike the strings in a piano, or other sounding elements of similar instruments. The frame, or each of the frames, above referred to, supports a driving shaft which is arranged by suitable mechanism to be connected with the take up roll or the delivery roll so that the music sheet may be drawn across the tracker bar in the desired direction. The driving shafts are connected to or driven by a single shaft which is either manually or electrically driven, as illustrated in the drawings.

The selection started continues to play unless it is interrupted by the operator, as will be hereinafter pointed out, or until it reaches a point near the end of the music sheet where an aperture in the music sheet registers with an aperture or duct in the tracker bar to produce actuation of a pneumatic which connects the rewind mechanism with the driving shaft. At the instant this rewind mechanism is connected with the driving shaft an electric circuit is closed, in which circuit is included the solenoid for controlling the second music sheet. The action of this solenoid like the one associated with the first music sheet, opens the vent, which in turn causes operation of the forward drive mechanism associated with the second music sheet. The first music sheet continues to rewind until it returns to its starting position, where an aperture in the music sheet registers with an aperture or duct in the tracker bar to cause collapse of a stop pneumatic which disconnects the rewind mechanism. Novel rewind and stop mechanism is employed so that only a single stop pneumatic is necessary for any number of music sheets. The second sheet continues to play until it reaches the end, at which time it is rewound and the third one started. This succession in action continues until the fourth or all succeeding sheets have been played, at which time the first one will again be started.

These and other features of my invention will be more clearly pointed out in the following description, in which reference is had to the accompanying drawings and in which,—

Figure 1 is a fragmentary front elevation of a piano provided with the automatic playing device of my invention, the front panel of the piano being removed.

Fig. 2 is a transverse section of the mechanism for controlling the vents leading to

the forward drive pneumatics; also showing the pneumatics controlling the rewind and stop mechanism, said last-mentioned pneumatics being supported on the same supports as the solenoids of said mechanism. 70

Fig. 3 is a front elevation of the supporting frame or one of the supporting frames, as the case may be, showing a part of the music sheet torn away and the rewind control and stop for rewind control; also 75 showing the means for manually controlling the rewind either for rewinding a music sheet, the unwound portion thereof, or any portion thereof.

Fig. 4 is an enlarged longitudinal section of the manual rewind and stop control taken on line 4—4, Fig. 3.

Fig. 5 is an enlarged transverse section taken on line 5—5, Fig. 4.

Fig. 6 is an enlarged transverse section taken on line 6—6, Fig. 4.

Fig. 7 is an enlarged vertical section taken on line 7—7, Fig. 1.

Fig. 8 is a vertical longitudinal section taken on line 8—8, Fig. 2, on a reduced 90 scale.

Fig. 9 is a longitudinal section taken on line 9—9, Fig. 2, on a reduced scale.

Fig. 10 is a horizontal section taken on line 10—10, Fig. 2.

Fig. 11 is a section similar to Fig. 2, showing parts of the electro-magnetic devices and the pneumatics and controls associated therewith in different positions.

Fig. 12 is a diagrammatic view of the 100 electric circuit wires controlling the various parts and devices.

Fig. 13 is a front elevation of the mechanism for actuating the take-up spool and the delivery spool.

Fig. 14 is a horizontal section taken on line 14—14, Fig. 4. Fig. 15 is a vertical longitudinal section taken on line 15—15, Fig. 7.

The piano casing is designated by the 110 numeral 20, which casing contains the strings, hammers co-operating therewith, pneumatic devices for operating the hammers, the main suction bellows communicating with the pneumatics, and rubber or 115 other tubing affording communication between the pneumatics and the tracker bar, all of which are well known in the art to which this invention appertains, and for this reason I have thought it unnecessary to 120 illustrate the same in the drawings.

Suitably supported within the piano casing is a board or shelf 21 which extends entirely across the inside of the piano, directly back of the front panel. Supported 125 from this board or shelf by means of bearings 22 or otherwise is a shaft 23 carrying bevel gears 24, 25, meshing respectively with bevel gears 26, 27, the bevel gear 26 being secured to a shaft 28 driven in any suitable 130

manner by an electric motor 29 or otherwise, while bevel gear 27 is secured to an upright or driving shaft 30 adapted to actuate, by means of suitable intermediate 5 mechanism, the several music sheet rolls to be hereinafter described.

Secured to the board or shelf 21 is a supporting frame 31 which carries a plurality of music sheets, as illustrated. In the particular representation of my invention illustrated I have shown three music sheets supported on a frame, but any other number may be supported on the frame or on a plurality of frames, as this is merely a matter 10 of choice and adaptation of my invention to meet certain conditions.

The supporting frame comprises a pair of spaced uprights 32 which are secured to the board or shelf 21 in any suitable manner. Extending between the uprights 32 are tracker bars 33 which are preferably adjustably mounted so that they may be shifted longitudinally to cause the apertures or 20 ducts contained therein to register correctly 25 with the apertures provided in the music sheets. Each tracker bar is associated with a delivery roll 34 and a take-up roll 35, bearings being provided in the uprights 32 of the supporting frame for the shafts 36 30 of the delivery rolls and for the shafts 36^a of the take-up rolls.

The shaft 30 is arranged parallel with one of the uprights 32 and a short distance from the same, a bearing 37 being provided at 35 the upper end of said upright to properly support said shaft, and a bearing 38 is provided in the board or shelf 21 in which the lower end of said shaft is journaled. This shaft may of course be otherwise journaled 40 to assure proper operation of the same.

Secured to the spindle 36 of each delivery roll is a bevel gear 39 which is adapted to mesh at certain times with a bevel gear 40 secured to the driving shaft 30, and the 45 spindle 36^a of each take-up roll has a spur gear 41 secured thereto adapted to mesh at certain times with a pinion 42. Suitable mechanism is provided to shift each of the bevel gears 39 into and out of mesh with its 50 coöperating bevel gear 40 of the driving shaft, and suitable means is also provided to shift each of the pinions 42 into and out of mesh with its coöperating spur gear 41 so that any delivery roll of the series or any 55 take-up roll may be actuated at will for winding the desired music sheet in a forward direction to the extent desired, or for rewinding the same after being fully paid out or only partly paid out, this being accomplished by means to be presently described.

I preferably provide suitable brackets 43, 44, on the upright of the supporting frame adjacent the shaft 30, said brackets having 60 the extremities of the spindles 36, 36^a of the

delivery and take-up rolls, respectively, journaled therein. The spindle of each delivery roll has its bevel gear 39 slidably mounted thereon, said gear being preferably splined to the shaft so that it may rotate 70 with the latter while being free to slide thereon, the hub of the gear being provided with an annular groove 45 into which the pins or studs 46 of a shifting yoke 47 extend, said yoke forming part of a bell-crank 75 lever 48. The outstanding arm of said bell-crank lever has one end of an actuating rod 49 secured thereto, the other end being fastened to an actuating pneumatic 50. One of these pneumatics is provided for each 80 music sheet and when collapsed they cause the bevel gears 39 to be moved into mesh with the bevel gears 40 on the driving shaft, it being of course understood that these pneumatics are actuated independent of 85 each other. The pinions 42 are secured to counter-shafts 51 which are mounted for rotation and lengthwise movement in the upright 32 adjacent the driving shaft 30 and in the adjacent brackets 44. Each of these 90 counter-shafts is moved lengthwise in its bearings by a bell-crank lever 52, receiving pivotal support from the upright 32 and having one end of an actuating rod 53 secured thereto, the other end of said actuating 95 rod being secured to an actuating pneumatic 54. The bellows 54, 50 may respectively be termed "winding and rewinding pneumatics."

Each of the counter-shafts 51 has a friction disk 55 secured thereto which is movable with the pinion 42 on said shaft and on the driving shaft 30 are three friction wheels 56 against which the friction disks 55 are adapted to engage. Each friction 100 disk is independently movable and serves to actuate its coöperating take-up roll. The rewinding pneumatic 50 and winding pneumatic 54 are actuated in the usual manner by causing them to collapse, each having 110 connection with the suction bellows of the instrument or with a suction chest controlled by a suction bellows, as is common. The expansion of these rewinding pneumatics may be effected by springs acting 115 against their movable boards or some part connected with the movable boards, as is common in the art. When any of the rewinding pneumatics is collapsed it causes downward movement of the actuating rod 120 49 connected therewith which in turn swings the bell-crank lever 48 connected to said rod and causes the coöperating bevel gear 39 to be moved lengthwise on the spindle 36 of the delivery roll. This causes engagement 125 of said bevel gear with the coöperating bevel gear 40 on the driving shaft 30, and as said shaft is in constant rotation, the delivery roll is actuated, causing the music sheet to be rewound, the rewinding continuing until 130

suitable stop mechanism is brought into action, as will be hereinafter described. Said stop mechanism is controlled either manually or automatically, the automatic actuation of the stop mechanism being effected by the introduction of air through one of the apertures or ducts of the tracker bar, said aperture or duct being connected by a suitable tube with said stop mechanism. 5 For this purpose the music sheet is provided with an aperture 57 adapted to register with said aperture or duct in the tracker bar when the sheet reaches the end of the selection. When one of the winding pneumatics 10 54 is collapsed it causes the coöperating counter-shaft 51 to slide in its bearings, which carries the friction disk 55 on said shaft in contact with one of the friction wheels 56 of the driving shaft and also 15 brings the pinion 42 adjacent said friction disk into mesh with the spur gear 41 on the spindle of the take-up roll 35. The driving shaft 30 through the medium of said friction wheel, friction disk, pinion and spur 20 gear rotates the take-up roll and causes the music sheet to be moved in a forward direction for playing, this movement of the music sheet being continued until the aperture 57 in the music sheet at the end of the selection 25 passes over an aperture or duct in the tracker bar which admits air to a pneumatic arranged to control the rewinding of the sheet. This rewinding, however, may be effected at any point in the forward movement 30 of the sheet, by mechanism to be presently referred to. The winding, and the rewinding of the music sheet is continued 35 so long as the rewinding pneumatic 54 or the rewinding pneumatic 50 is held in collapsed 40 position.

I will now describe the construction and operation of the controlling device for controlling the actuation of the pneumatics causing the winding and rewinding of the music 45 sheets. This device comprises a frame or block 58 having a chamber 59 provided with vent openings 60, there being three of these vent openings. Three passages 61 are also in communication with the chamber 59, to 50 each of which a tube 62 is connected. These tubes lead to the winding pneumatics 54.

Closing each of the passages 61 from the chamber 59 is a valve 63 having its stem extending upwardly through the top wall of the chamber, and in order to retain said valve in open position a spring 64 surrounds the stem and bears with one end against a pin 65 extending through the stem or some other suitable stop, and with its other end 60 against the top wall of said chamber.

Positioned adjacent each of the vent openings 60 is a solenoid 66 having a core 67 provided with an enlargement or head 68 at its lower end which serves as a valve to 65 close said vent opening, and each of the

cores has a collar or flange 69 thereon which is adapted to engage a spring-actuated horizontally-disposed retainer bar 70 when the core is elevated. The retainer bar is held in normal position, which is that shown in 70 full lines in Fig. 11, by springs 71 surrounding its spindle 72 at opposite ends, said spindle being mounted in brackets 73 secured to the frame 58, (Fig. 10). The inner side of this retainer bar is provided with 75 an inclined surface 74 which is adapted to be engaged by the collars or flanges 69 of said cores during the upward movement of the latter.

When one of the solenoids is energized, its 80 core will be attracted and moved upwardly. This movement of the core, whichever one it may be, causes the enlarged end thereof to open the coöperating vent opening 60 and the collar or flange 69 thereof to engage the 85 inclined surface 74 of the retainer bar, thereby moving the latter outwardly until said collar or flange passes the upper end of said bar, whereupon the springs 71 immediately return said bar to normal position. In this 90 manner the actuated core, which forms part of what may be termed a "vent-control," is retained in elevated or open position by the retainer bar, or "stop device," as it may be 95 termed.

Even though the solenoid again becomes deenergized, the core is retained in this elevated position until a second solenoid of the series is energized, whereby its coöperating core is attracted and actuates the 100 retainer bar in the manner described. This actuation of the retainer bar releases the core which was first attracted and thus causes the same to return to its normal position so as to close its coöperating vent opening 105 60. After the last-mentioned core has been thus returned, the retainer bar again returns to its normal position and retains the core which was last attracted in elevated position until the third solenoid is energized. The 110 same treatment is imparted to the third solenoid when the first core is energized. In fact, the arrangement herein illustrated is such that any one of the armatures will return to normal position to close its coöperating vent opening 60 when any other solenoid of the series is energized, regardless of whether the solenoids are energized in succession or otherwise.

When any of the cores are elevated, the 120 atmospheric air enters the coöperating vent opening 60 (Figs. 2 and 11) and passes through the chamber 59, thence through the passage 61, from which it enters the tube 62 in communication with said passage. 125 From the tube 62 it enters the winding pneumatic 54 for winding the coöperating music sheet, said pneumatic having a suction tube 75 connected thereto which acts to collapse the pneumatic immediately the 130

corresponding vent opening 60 is uncovered. This causes the friction disk 55 of the set of devices in which said pneumatic is included to be moved into contact with the coöperating friction wheel 56 on the driving shaft 30 and also causes the pinion 42 on the coöperating countershaft 51 to engage the spur gear 41 on the spindle of the coöperating take-up roll 35, thereby moving the 10 corresponding music sheet forwardly over the tracker bar associated therewith.

The mechanism employed for opening the 15 rewind vents and the mechanism for stopping the rewind after the music sheet has been returned to its original position is as follows,—

The aperture 57 formed in each music sheet at the end of the selection is adapted to pass over an aperture or duct 76 in the 20 tracker bar, and a tube 77 connects said aperture or duct with a valve chest 78, located in the frame or block 58, said chest having a suction chamber 79 connected with the suction bellows by a tube 80. An air 25 chamber 81 is arranged adjacent said suction chamber and a passage 82 connects said suction chamber with a rewind control pneumatic 83. A pneumatic or pouch 84 is arranged between the air chamber 81 and 30 the suction chamber 79 and when said air chamber is flushed by uncovering the aperture or duct 76 in the corresponding tracker bar, suction within said suction chamber draws the pneumatic or pouch 84 upwardly. 35 This causes a valve 85 to uncover a port 86 which connects the suction chamber with the passage 82, and thus the suction within said chamber acts to collapse the rewind control pneumatic. The latter has an extending arm 40 on its movable board and a metallic conducting or contact plate 88 applied to the underside of the projecting portion of said arm and bearing against the upper end of the stem of valve 63 so that when the 45 pneumatic 83 is collapsed it overcomes the action of the spring 64 surrounding said valve stem and causes said valve to be seated, thus closing the passage 61 which is in communication with the winding pneumatic 54. This therefore permits the winding pneumatic to expand so as to disengage the friction disk 55 from the friction wheel 56, and the pinion 42 from the spur gear 41, thereby stopping the forward winding 55 movement of the music sheet.

When the extending arm 87 of the pneumatic 83 is drawn downwardly, the contact plate 88 engages a contact plate 89 secured to the frame or block 58, the purpose of 60 which will be hereinafter described.

90 designates a rewind-stop pneumatic upon the collapsing of which the rewinding ceases. This pneumatic has a projecting arm 91 on its movable board engaging a 65 shoulder or stop 92 on the extending arm

87 of the rewind-control pneumatic 83. When the rewind control pneumatic 83 is collapsed, the arm 91 of the rewind stop pneumatic 90 becomes disengaged from said shoulder or stop 92, and the spring 93 70 within said pneumatic 90 causes the latter to expand. Said pneumatic 90 then engages a trip valve 94 which is spring-retained to close a vent opening 95, and which, when actuated, uncovers said vent opening. It 75 may here be stated that since there are three music sheets and tracker bars shown there are, in order to control each of the sheets separately; three rewinding pneumatics 50, three winding pneumatics 54; 80 three solenoids 66; three rewind control pneumatics 83, and three rewind stop pneumatics, each solenoid and each pneumatic having ducts or passages and valves or other controlling means associated therewith to 85 control the winding of each music sheet, and also the rewinding of the same independently. Said vent opening 95 is connected with the coöperating rewinding pneumatic 50 by a tube 96, and as said rewinding pneumatic is also in communication with the suction bellows of the instrument by means of a tube 97, the suction within said tube acting upon said rewinding pneumatic, when the vent opening 95 is uncovered, causes said 90 pneumatic to collapse, which moves the coöperating bevel gear 39 on the delivery spool of the music sheet into mesh with the mating bevel wheel 40 on the driving shaft 30. In this manner the rewinding of the 100 sheet is brought about. When the music sheet approaches the end of its rewinding movement, an aperture 98 therein at the commencement of the selection passes over an aperture or duct 99 in the tracker bar 105 which is in communication with a valve chest 100 by means of a tube 101, the tube being connected to an air chamber 102 in said chest which is separated from a suction chamber 103 therein by a pneumatic or 110 pouch 104. Suction chamber 103 has connection with the suction bellows of the instrument by a tube 105 and is separated from an air passage 106 by a wall 107, said air passage being in connection with the 115 rewind stop pneumatic 90.

When air is admitted to the aperture or duct 99 in the tracker bar, the suction within the suction chamber 103 causes the pneumatic or pouch 104 to be drawn upwardly. 120 This causes a valve 108 to uncover a port 109 between passage 106 and suction chamber 103 and places said suction chamber in communication with the rewind stop pneumatic 90, causing the latter to collapse 125 and the trip valve 94 to return to normal position so as to close the vent opening 95, thus shutting off the suction from the rewind pneumatic and permitting the same to expand. The expansion of said pneumatic 130

causes the coöperating bevel gear 39 to be moved out of mesh with the mating bevel gear 40 on the driving shaft and thus stops the rewinding movement of the music sheet.

5 As shown in Fig. 1, the music-sheets are arranged one above the other, and for convenience in further describing the invention I will refer to the uppermost music sheet as sheet No. 1, the second as sheet No. 2, and 10 the lowermost sheet as sheet No. 3. I will also refer to the solenoids shown in Fig. 1 as solenoids Nos. 1, 2 and 3, respectively, ranging successively from left to right. In Fig. 1 I have also shown three push buttons 15 110, for which may be substituted any other form of electric make-and-break device. These are shown in a horizontal series corresponding to the music sheets and the solenoids and are referred to successively as Nos. 20 1, 2 and 3 from right to left, and in addition thereto I have also shown a push button 111 for controlling the electric motor 29.

It is to be understood that each solenoid 25 has associated therewith one of the rewind-control pneumatics 83, and each of these pneumatics co-acts with a rewind stop pneumatic 90, also with one of the trip valves 94 so that there is a complete controlling device or a complete set of devices or mechanisms associated with each solenoid.

When for instance, the rewind-control pneumatic 83 associated with solenoid No. 1 is collapsed, the contact plate 88 thereof engages the co-acting contact plate 89, which 30 causes solenoid No. 2 to be energized, the core of said solenoid No. 2 is then drawn upwardly and causes the retainer bar 70 to be swung outwardly, thereby disengaging any other core that may be held elevated so that it may descend to close its co-operating vent opening 60. This upward movement of the core No. 2 uncovers the 35 vent opening 60 associated therewith and also causes a spring retained trip-valve 112 to uncover a vent opening 113, said vent opening being in communication with the air chamber 102 of valve chest 100 through the medium of a tube 114. This upward movement of the core therefore flushes chamber 102 and permits the suction in chamber 103 to open the valve 108 and cause collapse 40 of the rewind-stop pneumatic 90 in the same set. The upward movement of the core of the solenoid No. 2 immediately starts the forward movement of music sheet No. 2, and as the rewind-control pneumatic 83 is collapsed only when the forward movement of music sheet No. 1 is discontinued, it is clear 45 that the selection of sheet No. 2 is played immediately the selection of sheet No. 1 is finished. When the selection of sheet No. 2 is completed the rewind-control pneumatic 83 associated therewith collapses and the contact plates 88, 89 of set No. 2 are brought 50 into engagement, whereupon solenoid No. 3

is energized; the core thereof rising and causing, through intermediate means, the lowering of the core of the solenoid No. 2, thus stopping the forward winding movement of sheet No. 2, and immediately causing 70 the forward winding movement of sheet No. 3. When the end of the selection on sheet No. 3 is reached, the rewind-control pneumatic 83 associated therewith is caused to collapse and the contact plates 88, 89 of set No. 3 to be brought into engagement to energize solenoid No. 1. This causes the core of solenoid No. 3 to lower and stops the forward winding movement of sheet No. 3 75 while it places in immediate action the winding pneumatic of sheet No. 1. The continual playing of the instrument is thus controlled automatically and the selections are played successively.

I will now describe the push-button or 85 make and break device I employ for manually controlling the various movements of the music sheets.

These push buttons, which I have previously designated by the numerals 110 and 90 111, may be arranged at any convenient place on the instrument or at a distant point to be controlled by a person whose duty it is to see that the music is rendered in harmony with the scenes displayed upon a screen. 95 This may most conveniently be under the control of the operator of the machine projecting the pictures. I have shown in Fig. 1, button No. 1 at the right of the series. This button may be any ordinary push button 100 controlling an electric circuit and upon pressing button No. 1 an electric circuit is formed in which solenoid No. 1 is included. When this circuit is closed the core of solenoid No. 1 is energized and the vent opening 105 60 corresponding with core No. 1 uncovered. This causes the actuation of the winding pneumatic associated therewith, as hereinbefore described, and selection No. 1 to be played. This selection is continued so long 110 as it is in harmony with the pictures displayed on the screen, or it may be continued until completed, in which latter case the automatic mechanism comes into action to rewind the music sheet and simultaneously place another sheet in action. If, 115 however, the picture displayed requires another selection in order to harmonize therewith, push button No. 2 may be depressed, which establishes an electric circuit and energizes solenoid No. 2, causing the core 120 thereof to be elevated, the retainer bar 70 to be actuated and the core of solenoid No. 1 to descend. This causes sheet No. 1 to discontinue its forward movement, and sheet 125 No. 2 to commence its forward movement. At the same time, sheet No. 1 is being rewound so that it may be brought into action from the beginning of the selection thereon at any desired time. If button No. 3 is de- 130

pressed an electric circuit is established in which solenoid No. 3 is included. Said solenoid is thus energized and its core raised, whereupon the core of solenoid No. 2 descends and closes its coöperating vent opening 60. This causes the selection on sheet No. 3 to be played while that on sheet No. 2 is discontinued and said last-mentioned sheet rewound. Upon again depressing button No. 1, solenoid No. 1 is energized causing the selection on sheet No. 1 to be played and sheet No. 3 to be stopped and rewound. It is of course to be understood that prior to depressing any of the buttons 110, it is necessary to place the motor in action by depressing button 111 so that the drive shaft 30 is in continual motion and capable of imparting the desired motion to the music sheets when actuating the controlling devices.

In order that any selection may be played at any time, or any portion of the selection played, as may be desired, I have provided a series of stop and rewind-control buttons. In the particular arrangement shown a block 115 is provided in which stop buttons 116 and rewind buttons 117 are arranged. Each of the rewind buttons is seated in a pocket 118 formed in said block and has a shoulder 119 formed thereon. A spring 120 surrounds each rewind button between its shoulder and the bottom of the pocket, said spring serving to hold the button in its outermost position. Each of the rewind buttons extends into a chamber 121 formed in the block, and this chamber has contacts 122, 122^a secured to one of its walls. The extremity of each button has a contact 123 secured thereto which normally is in engagement with the co-acting contacts 122, 122^a. These contacts are included in an electric circuit in which the solenoids are included and normally close the circuit.

On the underside of this block are spring plates 124 secured to an extension 125 of said block by means of screws 126 or otherwise, and each plate has secured thereto a tube 127 which is normally closed by the inherent resiliency of said plate, a strip of felt 128 or other soft material being applied to the block against which the plate 124 bears, said strip of felt being positioned in line with the tube 127 so as to positively close the inner end of the same against the atmosphere when the plate 124 is in normal position.

A yoke member or stop 129 limits the outward movement of all spring plates 124. Plungers 130 are fitted in openings in the bottom wall of the chamber 121, and when any of the rewind buttons 117 is depressed, the inner end of the same engages its co-operating plunger and moves the latter outwardly so as to force the plate 124 associated therewith outwardly against the yoke

member, thus opening the coöperating tube 127.

It is of course to be understood that these rewind buttons correspond in number to the number of music sheets or sets of controlling devices employed.

The tubes 127 have connection with the tubes 77 which lead to the valve chest 78 so that when vent is given to any of the tubes 127 the suction in the corresponding chamber 79 of said chest causes the coöperating pneumatic or pouch 84 to be drawn upwardly, thus opening the valve 85 and placing the rewind control pneumatic 83 of the same set in communication with said suction chamber. This causes said pneumatic to collapse, whereupon the contact 88 of said pneumatic engages the corresponding contact 89 and energizes another solenoid so that the core of the latter is elevated in the manner hereinbefore described. This movement of the core will allow any other core that may be elevated to descend and close its coöperating vent opening 60, thus throwing the winding mechanism of the coöperating music sheet out of action. It is of course understood that it is only necessary to hold the rewind button 17 depressed until the contact 88 of the rewind control pneumatic engages the corresponding contact 89; such action occurring almost instantaneously.

The collapse of the rewind-control pneumatic 83 permits expansion of the rewind-stop pneumatic 90, which then acts to open the corresponding trip valve 94 so as to vent the rewinding pneumatic 50 and permit its being collapsed. This causes the rewinding of the music sheet roll until it reaches the beginning of the selection thereon, at which time the aperture 98 in said music sheet passes over the aperture or duct 99 in the tracker bar and causes the rewinding to cease; or the rewinding may be stopped manually at any point by depressing the stop button 116 included in the same set of devices.

The stop buttons 116 are held elevated by spring plates 131, best shown in Fig. 6. Each of these spring plates has a tube 132 attached thereto, the inner end of which is closed when said plate is raised into contact with the block 115, a piece of felt 132^a or other material being applied to the block to assure a positive closing of this tube. The outward movement of said spring plates are also limited by the yoke member or stop 129 and the inherent resiliency of said plate returns the latter to normal position so that the tubes 132 are flushed only when depressing the stop buttons. These tubes 132 are connected with the tube 101 leading from the aperture or duct 99 in the tracker bar to the valve chest 100 so that when any one of the stop buttons is depressed, the suction within the chamber 103

of said valve chest causes the collapse of the rewind-stop pneumatic 90 so that it engages the shoulder 119 of the coöperating rewind-control pneumatic 83.

5 It is therefore apparent that any one of the music sheets may be stopped at any point in its forward movement, and rewound and stopped at any point in its return movement so that any portion of a selection may 10 be played, and re-played as often as desired.

In Fig. 12 I have shown a diagrammatic view of the circuit wires, in which 133 represents the battery or source of electrical energy, 66 the three solenoids, 117 the circuit breakers, hereinbefore referred to as the rewind buttons, and 134 make and break devices, each of which comprises a pair of the contact plates 88, 89. The circuit breakers 117 may be termed button 15 switches, and the make-and-break devices 134 may be termed pneumatic switches, since they are actuated by the rewind-control pneumatics 83. The rewind buttons 117 constitute a single circuit breaker since the 20 circuit does not change upon depressing any of said buttons. The different rewind buttons, however, control the action of different rewind-control pneumatics.

A wire 136 connects one pole of the battery 30 133 with the circuit breakers 117, also with the pneumatic switches 134 and the push buttons 110, or similar make and break devices. A wire 137 connects the opposite pole of the battery with the solenoids 66, which 35 are connected with the push buttons 110 and the pneumatic switches 134 in the following manner,—solenoid No. 1 is connected with push button No. 1, by a wire 138, and with pneumatic switch No. 3, by wire 138 and a 40 wire 139. Solenoid No. 2 is connected with push button No. 2, by a wire 140 and with pneumatic switch No. 1 by wire 140 and a wire 141. Solenoid No. 3 is connected with push button No. 3 by a wire 142 and with 45 pneumatic switch No. 2 by wire 142 and a wire 143.

The operation of the device is as follows,—

Assuming all parts to be in normal position and the instrument idle, it is necessary 50 that the electric motor 29 be brought into action, which is done by depressing the button or other similar device 111. This causes the driving shaft 30, through the intermediaries described, to be rotated. A plurality 55 of such driving shafts may be rotated, or a single shaft employed regardless of the number of music sheet rolls to be played. It is understood that there are as many sets of devices as there are music sheets and that 60 in starting to play the instrument any one of the music sheets may be rotated. This merely requires the proper push button 110 to be depressed to cause the solenoid in the same set of devices to be energized, where- 65 upon the core thereof is elevated and raises

the trip valve 112 from its seat. This flushes the air chamber 102 of the valve chest 100, whereupon the suction in the suction chamber 103 of said chest acts to elevate the pneumatic or pouch 104 and raise the valve 70 108 from its seat so that the rewind-stop pneumatic 90 is collapsed, if not previously collapsed, and retained in such condition by arm 87 of pneumatic 83. The lifting of the core opens the vent opening 60 correspond- 75 ing therewith, which flushes the suction chamber of the winding pneumatic 54 of the same set, causing said pneumatic to collapse and the take-up roll of the corresponding music sheet to be placed in driving connec- 80 tion with the driving shaft 30. The selection on said sheet is then played until automatically stopped, or until stopped by depressing the corresponding rewind button 117. In either case the rewind-control 85 pneumatic 83 of the same set of devices is caused to collapse, which shuts off atmospheric air through the vent opening 60 by reason of the valve 63 becoming seated. The collapse of the rewind control pneumatic 90 allows the corresponding rewind-stop pneumatic 90 to expand and places the contact 88 of said rewind-control pneumatic in contact with the contact 89 electrically connected with one of the other solenoids of 95 the series. This energizes said solenoid and causes the core thereof to rise, whereupon retainer bar 70 is actuated and permits the core of the first set of devices to descend and close the vent opening 60 of said set, thus 100 making doubly sure that the rewinding pneumatic 50 cannot be actuated. At the time the rewind stop pneumatic expands it engages the trip valve 94, causing the vent opening 95 to be opened, whereupon the re- 105 winding pneumatic connected therewith by means of the tube 96 is caused to collapse and the associated music sheet to be re-wound.

When the core 67 of the second set of de- 110 vices is elevated, it raises the trip valve 112 from its seat, exposing the vent opening 113 and causing the corresponding rewind-stop pneumatic 90 to collapse. The expansion of the rewind-stop pneumatic 90 of the first 115 set actuates the coöperating trip valve 94 and opens the vent opening 95 which has connection with the rewinding pneumatic 50 of the first set through the medium of the tube 96 (see Fig. 1), whereupon said rewinding pneumatic is collapsed and places the driving mechanism of the delivery roll of the first set of devices into direct connection with the driving shaft 30, thus rewinding the music sheet of said set. Simultaneously 120 therewith the winding pneumatic 54 of the second set is caused to collapse, due to the opening of the vent opening 60 of said set, thus the second music sheet is moved forward for playing the selection thereon. This 125 130

change of selections is continued successively until all the selections are played when the first selection will be re-played.

Assuming the selection playing to be that 5 on the sheet of the second set of devices and that the picture displayed on a screen harmonizes only with a portion of said selection, which portion when played it is desired to replay, the rewind button No. 2 is depressed 10 so that vent is given through the corresponding tubes 127 and 77. This controls the actuation of the pneumatic or pouch 84 of the valve chest 78 whereupon the rewind-control pneumatic 83 is caused to collapse. This closes vent to the winding pneumatic 54 of the second set and causes the forward movement of the music sheet to cease. The collapse of said rewind-control pneumatic permits the rewind-stop pneumatic 90 of the same set to expand which in turn causes the trip valve 94 to be unseated from the vent opening 95, thus through the medium of the tube 96, allowing the suction to act on the rewinding pneumatic 50 which 25 immediately places the delivery roll of the music sheet in action to rewind the same, the extent of rewind being controlled by stop button No. 2, which flushes the air chamber 102 of valve chest 100 and causes 30 the rewind-stop pneumatic 90 to collapse.

When releasing the rewind button No. 2, the spring plate 124 associated therewith returns to normal position so that the vent to the air chamber 81 of the valve chest 78 35 is closed and the rewind-control pneumatic 83 immediately expands and permits the corresponding valve 63 to rise so that vent is given to the associated winding pneumatic, whereupon the desired portion of the selection 40 is replayed.

It is to be understood that the contacts 122, 123 of the rewind buttons merely serve to close the electric circuit, and when any one of the rewind buttons is depressed this 45 circuit is broken so that when the rewind-control pneumatic 83 is actuated, the contacts 88, 89 are made in a broken circuit and do not energize any of the solenoids. This action therefore retains the core of the solenoids of the same set in elevated position 50 so that the corresponding vent opening 60 remains open at its outer end, although momentarily closed by the valve 63 due to the rewind-control pneumatic being collapsed.

In order to shut off each of the tracker bars from the hammer pneumatics when the music sheet is being rewound or when it is stationary, I provide a cut-off 145 with 60 which the apertures or ducts in the tracker bar communicate, each of said apertures or ducts having connection with a divided passage 146 in said cut-off by means of a tube 147, and corresponding tubes 148 are connected with the divided passages of said cut-

off and the hammer pneumatics or other tone producing devices, also with any serving or control devices which it is desired to operate or control in a similar manner. This cut-off is also provided with a suction 70 chamber 149 in which pouches 150 are located that normally close the adjacent ends of the divided passages 146. When, however, any one of the openings in the tracker bar is uncovered by the music sheet, the suction 75 in the chamber 149 draws upon the pouch or pouches 150 of the corresponding divided passage and opens the adjacent ends of the same so that the two parts of the passage are in communication, as clearly shown 80 in Fig. 7, the suction chamber 149 being connected with the suction bellows of the instrument by a tube 151.

Having thus described my invention, what I claim is,—

1. A musical instrument comprising a plurality of tracker bars, a music sheet associated with each of the bars, mechanism for moving the music sheets either in a forward or reverse direction over the tracker bars, 90 means for automatically causing said mechanism to rewind a music sheet when it has been played, and devices for starting a second sheet immediately after the first mentioned sheet has been played, said devices 95 being controlled either automatically or manually.

2. A musical instrument comprising a plurality of tracker bars, a music sheet associated with each of the bars, means for 100 moving the music sheets either in a forward or reverse direction over the tracker bars, and devices controlled either manually or automatically for starting a second sheet immediately after the first-mentioned sheet 105 has been played.

3. A musical instrument comprising a plurality of tracker bars, a music sheet associated with each of said bars, mechanism for moving the music sheets either in a forward or reverse direction over the tracker bars, means for automatically causing said mechanism to rewind a music sheet when it has been played, devices for automatically 110 starting a second sheet immediately after 115 the first-mentioned sheet has been played, and manually-controlled electrically-operated mechanism for placing any sheet in action commencing at any point thereof.

4. A musical instrument provided with a 120 plurality of tracker bars each associated with a music sheet, means controlled from the tracker bars for rewinding the music sheets as they have been played, means for stopping them when they have been re-wound, and electrical means for starting any other of the remaining sheets.

5. In a musical instrument the combination of a plurality of tracker bars, a music sheet associated with each of the bars, means 130

for moving the music sheets in a forward direction, pneumatics for connecting the music sheets with said means, solenoids, vents for said pneumatics controlled by the 5 cores of said solenoids, and a retaining means for retaining said cores in attracted position.

6. In a multi-sheet musical instrument, the combination of a plurality of tracker 10 bars, a music sheet associated with each tracker bar, driving mechanism for rewinding the music sheets, a pneumatic for each sheet adapted to connect the sheet with the driving mechanism, a vent for each pneumatic, and a vent control for each vent.

7. In a multi-sheet musical instrument, the combination of a plurality of tracker bars, a music sheet associated with each tracker bar, driving mechanism for rewinding 20 the music sheets, a pneumatic for each sheet adapted to connect the sheet with said driving mechanism, a vent for each pneumatic, a vent control for each vent, means for individually operating said vent controls, and a single stop device adapted to hold each actuated vent control in spaced relation to its coöperating vent to move the vent controls to closed position.

8. In a multi-sheet musical instrument, 30 the combination of a plurality of tracker bars, a music sheet associated with each tracker bar, driving mechanism for rewinding the music sheets, a pneumatic for each sheet adapted to connect the sheet with said driving mechanism, a vent for each pneumatic, a pneumatic vent control for each vent, means for individually actuating said vent controls, and means for retaining each vent control in actuated position.

40 9. In a multi-sheet musical instrument, the combination of a plurality of tracker bars, a music sheet associated with each tracker bar, driving mechanism for rewinding the music sheets, a pneumatic for each sheet adapted to connect the sheet with said driving mechanism, a vent for each pneumatic, a pneumatic vent control for each vent, means for individually actuating said vent controls, and a stop device adapted to 45 retain each actuated vent control in open position.

50 10. In a multi-sheet musical instrument, the combination of a plurality of tracker bars, a music sheet associated with each tracker bar, driving mechanism for rewinding the music sheets, a pneumatic for each sheet adapted to connect the sheet with said driving mechanism, a vent for each pneumatic, a pneumatic vent control for each 55 vent, means for individually actuating each vent control to bring the same into open position, and means to be actuated by said vent controls to permit the retained vent control to lower and close its coöperating 60 65 vent.

11. In a self-playing musical instrument, the combination of a plurality of tracker bars, a music sheet coöperating with each of the bars, means for selectively driving the sheets in a forward direction to any desired extent, means for selectively rewinding the sheets to any desired extent, and devices for automatically operating said selective driving means to start a music sheet in a forward direction when another music sheet is 70 being rewound.

12. A musical instrument having a plurality of music sheets, means for winding and rewinding said sheets, manually controlled devices for causing any music sheet 80 to be rewound at any time and automatic devices for causing any one of said sheets to be driven in a forward direction, said automatic devices being in part inactive when said manually-controlled devices are brought 85 into action.

13. A musical instrument having a plurality of music sheets, means for winding and rewinding said sheets, and manually controlled devices for causing any music sheet 90 to be wholly or partly rewound at any time, and means for commencing the winding of any desired sheet from any desired point thereof.

14. In a musical instrument, the combination of a plurality of tracker bars, each co-operating with a music sheet, drive mechanism, electro-magnetic devices associated with each sheet whereby the forward movement of the same is controlled, means for rewinding each of the music sheets, a circuit closer for each of the rewind means, and an electric circuit for each electro-magnetic device, said circuit including in series the circuit closer of the rewinding mechanism of 105 the preceding music roll.

15. In a musical instrument, the combination of a plurality of tracker bars, each co-operating with a music sheet, drive mechanism, electro-magnetic devices associated 110 with each sheet whereby the forward movement of the same is controlled, means for rewinding each of the music sheets, a circuit closer for each of the rewind means, and an electric circuit for each electro-magnetic device, said circuit including in series the circuit closer of the rewinding mechanism 115 of the preceding music roll, and a manually operated circuit breaker.

16. A musical instrument having a plurality of tracker bars, each associated with a music sheet, and manually controlled means for rewinding any music sheet at any time to any degree desired, and means for commencing the winding of said sheet from 120 the point at which it was stopped.

17. A musical instrument comprising a plurality of tracker bars, a music sheet associated with each of said bars, and selective mechanism comprising means for causing 125 130

any one of said note sheets to be moved in a forward direction and means to simultaneously rewind any other music sheet of the series.

- 5 18. A musical instrument comprising a plurality of tracker bars, a music sheet associated with each of said bars, and mechanism comprising means for causing any one of said music sheets to be moved in a forward direction to any extent desired, and means for rewinding said music sheet to any extent desired.
- 10 19. A musical instrument comprising a plurality of tracker bars, a music sheet associated with each of said bars, and selective mechanism comprising means for selectively playing said music sheets and rewinding each sheet when played, and means for manually controlling the extent of forward 15 or rewinding movement of each sheet.
- 20 20. A musical instrument comprising a plurality of tracker bars, a music sheet cooperating with each tracker bar, means to drive the sheets in a forward direction, 25 means for causing any desired sheet to be connected separately with the driving means and means for simultaneously partially or completely rewinding any sheet which may be played at the time of making such connection.

- 30 21. In a musical instrument, the combination of a plurality of tracker bars, a music sheet associated with each tracker bar, means for moving the music sheets sep-

arately in a forward direction, and mechanism for causing said first-mentioned means to move any desired sheet in one direction and simultaneously move another sheet in an opposite direction, either or both to any extent desired.

40 22. In a multi-sheet musical instrument, the combination of a plurality of tracker bars, a music sheet associated with each tracker bar, drive mechanism for driving each of said music sheets separately in a forward or in a reverse direction, a pneumatic for each sheet adapted to connect the sheet with said drive mechanism, a vent for each pneumatic, a vent control for each vent, and a stop device to retain the vent controls in 45 open position, each vent control serving to control certain action of the remaining vent control or controls.

23. The combination with a tracker bar, a music sheet and a delivery roll and take-up 50 roll for said music sheet, of driving mechanism, a forward connector for connecting the take-up roll of the music sheet with said driving mechanism, a pneumatic for controlling the forward connector, a rewind 55 connector for connecting the delivery roll of the music sheet with said driving mechanism, a pneumatic for controlling said rewind connector, and a vent for the last-mentioned pneumatic.

60 In testimony whereof I affix my signature.

MAX WEISBERG.
